UNITED STATES PATENT OFFICE

WILLIAM M. SPINDLER, OF NEW ORLEANS, LOUISIANA

AUTOMATIC WINDOW FASTENER

Application filed January 18, 1930. Serial No. 421,838.

This invention relates to window fasteners or latches and has special reference to an automatic or self latching window latch adapted for use in connection with sliding sash.

One important object of the invention is to provide an improved general construction of latches of this class.

A second important object of the invention is to provide an improved latch of this description so arranged that the act of closing the window will effect latching of the same so that one cannot, without deliberate intention, leave the window unlatched when closing the same.

A third important object of the invention is to provide, in connection with such a latch novel means whereby the latch may, if desired, be rendered inoperative as to securing the window when it is closed.

With the above and other objects in view, as will be presently apparent, the invention consists in general of certain novel details of construction and combinations of parts hereinafter fully described, illustrated in the accompanying drawings and specifically claimed.

In the accompanying drawings, like characters of reference indicate like parts in the several views, and:-

Figure 1 is an elevation, from the inside, of a window frame and its sashes and showing the application of the device thereto.

Figure 2 is a greatly enlarged section on the line 2-2 of Figure 1.

Figure 3 is a view similar to Figure 2 but showing one side of the latch housing removed to disclose the working parts, the device being shown in latching position.

Figure 4 is a view similar to Figure 3 but with the parts in released position.

Figure 5 is a detail section on the line 5-5 of Figure 2 and showing the latch in plan.

Figure 6 is a face view of the keeper and latch actuating dog carried thereby, the dog being in position to cause engagement of the latch proper with the keeper.

Figure 7 is a view similar to Figure 6 but with the dog thrown into inoperative position for releasing the latch from the keeper

if the window be closed and for preventing latching of the window upon closing if the window be open.

Figure 8 is a face view of the latch housing from the outer side of the same.

Figure 9 is a section through the latch housing of a modified form of the device and showing the working parts in elevation.

Figure 10 is a view similar to Figure 9 but showing a second modification.

Figure 11 is an elevation of the rear end of the modification shown in Figure 10.

In the embodiments of the invention herein disclosed it will be seen that the device is shown as applied to an ordinary type of window having a frame 10 having the usual sliding sashes 11. The upper sash has the side stiles 12 and the bottom or meeting rail 13, the lower sash being similarly provided with side stiles 14 and a top or meeting rail 15.

The device itself consists of two parts, a latch and its housing and a keeper and its dog. The keeper consists of a base plate 16 which is gained into one of the stiles 12 adjacent the meeting rail 13 and is there secured by the screws 17.

Projecting inwardly of the window from the lower part of this base is a lug 18 provided on its under side with a channel 19 and this lug constitutes the part of the keeper that is engaged by the latch proper in latching position. The upper edge of this lug is undercut, as shown in Figures 2, 3 and 4, to receive the bevelled under edge of a dog 20 secured by a pivot 21 at one of its lower corners to the base 16. This dog normally lies transversely of the base as shown in Figure 6 but it may be raised to the position shown in Figure 7, the free edge of the dog being corrugated so as to afford ready engagement by the thumb of the operator as may be seen at 22.

Also, the dog is provided near the pivot with a stop lug 23 so that when the dog is in raised position this lug 23 will engage against the side of the lug 18 and thus limit movement of the dog in one direction, the lug 18 also limiting movement of the dog in the opposite direction. The purpose of the dog being swingingly mounted in this manner will be presently explained.

The other part of the device consists of a rectangular housing 24 having lateral base flanges 25 provided with suitable screw holes so that it may be secured to the meeting rail 15 of the lower sash by the screws 26. Projecting outwardly from the upper part of this housing in the direction of the upper sash is a plunger 27 having a bevelled nose 28, the bevel being on the under side of the nose. 10 This plunger has a stem 29 which slides through the back wall of the housing and is surrounded by a coiled compression spring 30 by which the plunger is urged outwardly. Depending from this plunger is a lug 31 having a notch 32 extending upwardly from its lower edge. In the form of the invention shown in Figures 3 and 4 this notch receives the upper end of a lever 33 mounted intermediate its ends on a pivot 34 secured in the 20 sides of the housing. The lower end of this lever is extended forwardly to project out of an opening in the front wall of the housing so that when thus projected it may engage under the lug 18 and enter the channel 19. 25 In the form of the invention shown in Figure 9 the notch 32 receives the upper end of a lever 35 pivoted on a pin 36 and having its lower end engaging in a notch 37 formed in the upper face of a sliding hook 38 which 30 slides in and out of a suitable opening in the front wall of the housing, the rear end of this hook sliding through a partition 39 fixed within the housing. The forward end of this hook 38, like the lower hook end of the lever 33, engages in the channel 19 when projected forwardly.

In each of these modifications the arrangement is such that whenever the plunger 27 is protracted the hook is retracted and cannot 40 engage the keeper to latch the window. When, however, the plunger is forced back against the action of the spring the hook will be protracted and will thus be in latching position. The dog 20 is the element of the 45 mechanism which effects this forcing of the plunger inwardly since, when the dog is turned down as in Figure 6, the bevel nose of the plunger engages the dog as the window is moved to closed position, this engagement taking place just before the hook is in position 50 to engage beneath the lug 18. Thus, as the window is closed the hook is forced outwardly and engages the keeper thus automatically latching the window.

55 When it is desired to open the window the dog is thrown up to the position of Figure 7 whereupon the plunger is protracted by the spring and the hook is retracted. If it be desired to close the window without latching it, it is merely necessary to raise the dog before closing the window so that the plunger will remain protracted and the hook retracted even if the window is closed.

In the form of the invention shown in Figures 10 and 11 there is provided a housing 40

similar to the housings previously described and having a plunger 41 mounted to slide through the front and rear walls. The forward end of this plunger is squared and provided with a bevelled nose 42 and a coiled 70 spring 43 urges the plunger into keeper engaging position. A lug 44 projects downwardly from the squared portion of the plunger to engage the upper forked end 45 of a hook member 46 pivoted within the casing as at 47. A button 48 is formed on the rear end of this plunger and a locking arm 49 is pivoted to the rear face of the housing 40 as at 50 so that it may swing between the free position shown in full lines in Figure 80 11 and the locking position. By this means, the operation being otherwise the same as in the other forms, the plunger may be held from protraction so that the hook cannot disengage from the keeper and thus the window 85 cannot be raised by a person outside the house. It will be noted from Figure 11 that the safety arm automatically engages beneath the button upon the plunger being retracted, the lower end of the arm being 90 weighted for this purpose.

There has thus been provided a simple and efficient device of the kind described and for the purpose specified.

It is obvious that many minor changes may 95 be made in the form and construction of the invention without departing from the material principles thereof. It is not therefore desired to confine the invention to the exact form herein shown and described but it is 100 desired to include all such as properly come within the scope of the claims.

Having thus described the invention, what is claimed as new, is:—

1. A window fastener including a keeper and a latch respectively adapted to be secured to parts of a window movable toward and from each other to close and open the window, said latch including a housing, a latch hook mounted in the housing for protraction therefrom into latching engagement with the keeper, a plunger normally protracted from said housing and having a bevelled nose engaging the keeper upon closing the window to retract the plunger, and operative connection between the latch hook and plunger to protract the hook as the plunger is retracted. 105 110 115

2. A window fastener including a keeper and a latch respectively adapted to be secured to parts of a window movable toward and from each other to close and open the window, said latch including a housing, a latch hook mounted in the housing for protraction therefrom into latching engagement with the keeper, a plunger normally protracted from 120 said housing and having a bevelled nose engaging the keeper upon closing the window to retract the plunger, operative connection 125 between the latch hook and plunger to pro- 130

tract the hook as the plunger is retracted, and a spring urging said plunger to protracted position.

3. A window fastener including a keeper and a latch respectively adapted to be secured to parts of a window movable toward and from each other to close and open the window, said latch including a latch hook movable into and out of latching engagement with the keeper, and means engageable with the keeper upon closing of the window to move the latch hook into said engagement, said keeper including a member movable manually into and out of the path of said means to actuate the means when in the path thereof.

4. A window fastener including a keeper and a latch respectively adapted to be secured to parts of a window movable toward and from each other to close and open the window, said latch including a latch hook movable into and out of latching engagement with the keeper, means engageable with the keeper upon closing of the window to move the latch hook into said engagement, and a spring urging the latch hook out of engagement with said keeper, said keeper including a member movable manually into and out of the path of said means to actuate the means when in the path thereof.

5. A window fastener including a keeper and a latch respectively adapted to be secured to parts of a window movable toward and from each other to close and open the window, said latch including a housing, a latch hook mounted in the housing for protraction therefrom into latching engagement with the keeper, a plunger normally protracted from said housing and having a bevelled nose engaging the keeper upon closing the window to retract the plunger, and operative connection between the latch hook and plunger to protract the hook as the plunger is retracted, said keeper including a member movable manually into and out of the path of said plunger to actuate the plunger when in the path thereof.

6. A window fastener including a keeper and a latch respectively adapted to be secured to parts of a window movable toward and from each other to close and open the window, said latch including a housing, a latch hook mounted in the housing for protraction therefrom into latching engagement with the keeper, a plunger normally protracted from said housing and having a bevelled nose engaging the keeper upon closing the window to retract the plunger, operative connection between the latch hook and plunger to protract the hook as the plunger is retracted, and a spring urging said plunger to protracted position, said keeper including a member movable manually into and out of the path of said plunger to actuate the plunger when in the path thereof.

7. A window fastener including a keeper

and a latch respectively adapted to be secured to parts of a window movable toward and from each other to close and open the window, said latch including a latch hook movable into and out of latching engagement with the keeper, a plunger engageable with the keeper upon closing of the window to move the latch hook into said engagement, and a manually releasable stop engaging the plunger upon retraction thereof to hold the same against protraction.

8. A window fastener including a keeper and a latch respectively adapted to be secured to parts of a window movable toward and from each other to close and open the window, said latch including a latch hook movable into and out of latching engagement with the keeper, means engageable with the keeper upon closing of the window to move the latch hook into said engagement, and a stop for holding the hook in keeper engaging position, said stop being positioned for manual release.

9. A window fastener including a keeper and a latch respectively adapted to be secured to parts of a window movable toward and from each other to close and open the window, said latch including a latch hook movable into and out of latching engagement with the keeper, a plunger engageable with the keeper upon closing of the window to move the latch hook into said engagement, a spring urging the latch hook out of engagement with said keeper, and a manually releasable stop engaging the plunger upon retraction thereof to hold the same against protraction.

10. A window fastener including a keeper and a latch respectively adapted to be secured to parts of a window movable toward and from each other to close and open the window, said latch including a housing, a latch hook mounted in the housing for protraction therefrom into latching engagement with the keeper, a plunger engageable with the keeper upon closing of the window to protract the latch hook, said keeper including a member movable manually into and out of the path of said means to actuate the means when in the path thereof, and a manually releasable stop engaging the plunger upon retraction thereof to hold the same against protraction.

11. A window fastener including a keeper and a latch respectively adapted to be secured to the upper and lower sash of a window having sliding sash, said latch including a housing having a plunger mounted in its upper part provided with a normally protracted nose positioned to engage the keeper upon closing movement of the window and held in retracted position by the keeper when the window is closed, a latch hook in the lower part of the housing in normal retracted
